UNITED STATES PATENT OFFICE.

LOTHAR VON DABROWSKI, OF CHICAGO, ILLINOIS.

LAY-DOWN CAR-STAKE.

No. 826,150.

Specification of Letters Patent.

Patented July 17, 1906.

Application filed April 6, 1906. Serial No. 310,256.

To all whom it may concern:

Be it known that I, LOTHAR VON DABROWSKI, a citizen of the United States, residing at Chicago, in the county of Cook and State 5 of Illinois, have invented new and useful Improvements in Lay-Down Car-Stakes, of which the following is a specification.

The object of this invention is to provide a lay-down stake for railway flat-cars of simple 10 and inexpensive construction which will avoid the inconvenience and expense of providing new stakes according to the custom which now obtains when the car is to be re-loaded with lumber or similar material.

15 In the accompanying drawings, illustrating the preferred embodiment of my invention, Figure 1 is a top view of a portion of the side sill of a car, showing my invention applied thereto, the stake being shown in lay-down position in dotted lines. Fig. 2 is a side view. Fig. 3 is an end view. Figs. 4, 5, and 6 are respectively top, side, and end views of the main casting of the pocket. Figs. 7, 8, and 9 are similar views of the pivoted side of the pocket.

20 The pocket, which is fastened to the car-sill 1 to receive the stake 2, corresponds in shape to the ordinary stake-pocket and is designed to receive a stake of the Master Car-Builders' standard size; but it will be understood that the size and proportion of the various parts may be varied in such respects as shall be found necessary or desirable to suit 25 various conditions which may from time to time arise.

30 The stake-pocket comprises a main casting 3, Figs. 4 to 6, which provides three sides of the pocket, and another casting 4, Figs. 7 to 9, which is pivoted to the main casting and provides 35 the other side of the pocket. The pocket is thus composed of two principal parts which together form a pocket of the ordinary shape. The two parts of the pocket are connected together, and the pocket is secured 40 to the car-sill 1 by a U-bolt 5, which lies in a groove 6, provided for it in the main part or casting 3, and passes through openings 7 in ears 7' on the outer side of the pivoted part or casting 4, which forms the movable or swinging side of the pocket. The main part or casting 3 is further secured to the car-sill by bolts 8, passing through openings 8' in the webs 9, 9' and through the car-sill. The U-bolt passes through an opening 55 6' in web 9 and also through a sleeve or ferrule 10, which is arranged in the openings 7

of the ears 7' and abuts at its ends against the ears 11 on the main part or casting 3, which ears are provided with openings 11' for the U-bolt. This sleeve or ferrule constitutes a spacing device which prevents the main part or casting from being drawn out of shape or broken when the securing-bolts are tightened and also prevents the main part or casting from being sprung together in a manner which would prevent the movable side from swinging freely therein. A hook 12 is pivotally connected to the car-sill by an eye-bolt 12', and it is arranged to enter an opening 13 in the lug 13' at the top of the movable side 4. The stake 2 is rigidly secured to the movable side by bolts 14, which pass through openings 14' in said side, and the stake is beveled at its lower end 15, so that it can swing in the pocket to a horizontal position, 70 as indicated by dotted lines in Fig. 1. A bracket 16 of any suitable character is arranged on the sill to support the stake when in horizontal position. The part or casting 3 is provided with webs 17, and the part or 80 casting 4, which constitutes the movable side of the pocket, is provided with webs 18. The webs 17 coöperate with the sleeve or ferrule 10 in strengthening the part 13 to prevent it from bending or breaking under the tension 85 or strain applied thereto by the bolts. I have shown a wooden stake and a pocket designed to receive this particular stake in the accompanying drawings; but it will be understood that I may use a metal stake of any 90 kind and fit the stake in the pocket by the use of filler-blocks of any character. The two parts of the pocket can be made of cast-iron, malleable iron, cast-steel, or any other suitable material.

95 With my invention the same stake can be used until broken or worn out without removing it from the car. When the stakes are to be used, they are swung into upright position and locked by means of the hooks, and when the car is to be loaded with rails, car-wheels, and other heavy material the stakes can be quickly swung into lay-down position by simply releasing the hooks. At the present time it is customary when loading cars with lumber in the lumber districts to make new stakes and fit them in the pockets each time the car is loaded, for when the car is unloaded the stakes are removed or broken off and thrown away. This is often due to carelessness and a disregard for the value of the material represented by the

stakes and also because these flat-cars are often loaded with heavy material, such as rails and car-wheels, and it is necessary that there shall be no obstruction at the side of the car during this loading operation. It may therefore be said to be a general custom obtaining at present to treat the stakes as waste material to be thrown away after they are once used. This represents a considerable loss, especially now that lumber is becoming more scarce and valuable. My invention provides a stake permanently fixed to the car which will fold down below the platform 19 when not in use and which can be readily arranged in position for use when desired.

What I claim, and desire to secure by Letters Patent, is—

1. The combination of a car-stake pocket having a side constructed to swing lengthwise of the car, a stake fastened to said side to swing therewith, and means for securing said side and stake in fixed position.
2. The combination of a car-stake pocket having a side movable lengthwise of the car, a stake fastened to said side to move therewith, and means for securing said side and stake in upright position.
3. The combination of a car-stake pocket having a side movable lengthwise of the car, a stake fastened to said side to move therewith, and a hook for securing said side and stake in fixed position.
4. The combination of a car-stake pocket comprising a fixed part and a relatively movable part, said relatively movable part comprising one side of the pocket, a car-stake fastened to said movable part, said car-stake being beveled at its lower end to permit it to move in the pocket with the movable side,

and means for securing said side and stake in fixed position.

5. The combination of a car-stake pocket consisting of a fixed part comprising three sides of the pocket, and a relatively movable part comprising the other side of the pocket, a car-stake fastened to said movable part and arranged to swing in said pocket, and a hook for securing said movable part and stake in fixed position.

6. The combination of a car-stake pocket consisting of a fixed part and a relatively movable part, a U-bolt for pivotally connecting the movable part to the fixed part and for securing the pocket to a car-sill, a car-stake fastened to said movable part, and means for securing said side and stake in fixed position.

7. The combination of a car-stake pocket consisting of a fixed part comprising three sides of the pocket and a relatively movable part comprising the other side of the pocket, ears on the fixed part and on the movable part, said ears being provided with openings, a sleeve arranged in the openings in the ears on the movable part and abutting against the ears on the fixed part, a U-bolt passing through said sleeves and the openings in said ears and securing said pocket to a car-sill, a car-stake fastened to said movable part and beveled at its lower end to permit said stake to swing with the movable part from upright to horizontal position, and a hook on the car-sill arranged to engage the movable part to secure said movable part and stake in fixed position.
